PUMP-CONTROL AND REGISTER-RESETTING INTERLOCK FOR LIQUID DISPENSING APPARATUS

William P. Miteik, Westfield, Mass., assignor to Gilbert & Barker Manufacturing Company, West Springfield, Mass., a corporation of Massachusetts

Application March 3, 1955, Serial No. 491,876

2 Claims. (Cl. 222—34)

This invention relates to an improved mechanism for interlocking the control member for the dispensing means of a liquid dispensing apparatus, such for example as a gasoline dispensing apparatus, with the means for resetting the register that indicates the quantities dispensed, for the purpose of preventing dispensing during resetting and resetting during dispensing and for compelling resetting after each dispensing operation.

The invention has for an object the provision of an improved interlock mechanism of the type described that is especially adapted for use with a register-resetting means of the type in which the reset shaft is axially shiftable from an inactive position to an active position and, while in the latter position is rotated one revolution in one direction to effect the resetting.

The invention will be disclosed with reference to one illustrative embodiment of it in the accompanying drawings, in which

Fig. 1 is a sectional elevational view of a dispensing apparatus embodying the invention;

Fig. 2 is a fragmentary cross sectional view taken on the line 2—2 of Fig. 1 and drawn to a larger scale and showing the interlock mechanism positioned to permit resetting of the register and to prevent pumping;

Fig. 3 is a fragmentary sectional plan view taken on the line 3—3 of Fig. 2;

Fig. 4 is a view taken similarly to Fig. 2 but showing the interlock mechanism positioned to permit pumping and to prevent resetting of the register;

Fig. 5 is a fragmentary cross sectional view taken on the line 5—5 of Fig. 3 and showing the control member latched in "off" position;

Fig. 6 is a view taken similarly to Fig. 5 but showing a different relative positioning of certain parts and showing the control member in "on" position; and

Fig. 7 is a fragmentary sectional plan view showing the mounting of the latching means for the dispensing control member.

Referring to these drawings and first to Fig. 1 thereof, the invention is shown, by way of illustrative example, as embodied in a gasoline dispensing apparatus of well known form. This apparatus includes a dispensing means a pump 1 driven by an electric motor 2 through the belt 3 and pulleys 4 and 5 and adapted to draw up fluid, such as gasoline, from an underground storage tank (not shown) through a suction pipe 6 and force it outwardly through a dispensing conduit, which includes a flexible hose 7 having on its outlet end a valved hose nozzle 8. This dispensing conduit has interposed therein an air separator 9 and a displacement meter 10. This conduit includes a pipe 11, which connects the outlet of the pump to the inlet of the separator, a pipe 12, which connects the outlet of the separator to the inlet of the meter, and a pipe 13, which connects the outlet of the meter to the hose 7. The element shown at 14 affords a liquid-recovery chamber, that receives liquid and/or air from the air separator 9 by way of a pipe 15, vents the air to the atmosphere by way of a pipe 16 and returns

2

the liquid to the suction side of pump 1 by way of a pipe 17.

The elements described, except for hose 7, its nozzle 8 and a portion of pipe 13, are suitably supported as indicated, from a suitable frame, herein shown as consisting of four corner posts 18 fixed to and upstanding from a base 19, and a top support 20 which interconnects the upper ends of the corner posts. This frame is enclosed by a suitable casing having four side walls 21 upstanding from the base and a cap 22 surmounting the upper ends of such sides.

The meter 10 drives through a vertical shaft 23 a register 24 mounted on top of the cap 22 and having suitable indicating means to show the quantity of liquid dispensed. These means include a plurality of counter wheels 25 which are revoluble around a shaft 26 and are suitably driven from the meter shaft 23. The numbers on these wheels are visible through windows 27 provided in the casing of the meter. The shaft 26 is utilized for resetting the counter wheels to zero and is provided with a knob 28 whereby it may be manually moved for this purpose. To reset the register, the knob 28 is pushed to the right, as viewed in Fig. 1 from a position, in which it is inactive for resetting, as far as it will go to a second position, in which it is active for resetting, and then rotated one complete revolution in the direction in which the counter wheels count or counterclockwise as viewed in Fig. 2. The register is a standard article of commerce and its construction insofar as the counting and resetting operations of the counter wheels are concerned is shown in the Harvey N. Bliss Patent No. 2,610,794, granted September 16, 1952, to Veede-Root, Incorporated. Its shutter operating means is shown in the George W. White Patent No. 2,550,103, granted April 24, 1951, to the same assignee. Reference is made to these patents for a more complete disclosure of the meter if such is necessary or desired.

The pump motor 2 has a suitable switch, mounted within a housing 29 and operable by a lever 30, shown elevated in "off" position in Fig. 1. This switch is operable from outside the pump casing by means of a manually operable control member 31 and suitable connections. This control member is fixed to the outer end of a shaft 32 which is rotatably mounted in a bracket 33, suitably fixed to a cross plate 34. The latter (Figs. 2 and 3) is fixed at its ends one to each of a pair of the corner posts 18 and spans the space between them. The bracket 33 extends for the most part outside the pump casing and forms a support for the hose nozzle 8 when the latter is not in use. A lug 31' on the control member abuts the lower part of the guard of the hose nozzle, as indicated in Fig. 3, to prevent movement of the member in the direction necessary to close the motor switch. The shaft 32 extends inside the pump housing and has its inner end supported in a second and parallel cross plate 36, which is also fixed at its ends to the above-named pair of corner posts. Fixed to shaft 32 at a location between the two cross plates 34 and 36 is an arm 37, which is connected by a link 38 to the outer end of an arm 39, the inner end of which is fixed to a counter-shaft 40. The latter is supported at its ends one in each of two cross plates 41, each of which is fixed at its ends to a pair of corner posts 18. Also fixed to shaft 40 is an arm 42 which is connected by a link 43 (preferably adjustable as to length as shown) to the described switch lever 30. The control member 31, when positioned as shown in Fig. 5, maintains, through the links and levers described, the control member 31 elevated in "off" or inactive position. Figs. 2 and 4 show shaft 32 in the same position as Fig. 5. In this position, a projection 44 fixed to shaft 32 abuts a stop 45 struck up from cross plate 34. The control member, when released, is mov-

able clockwise as viewed in Fig. 5, until a second projection 46 fixed to shaft 32 abuts the stop 45 as shown in Fig. 6. When the shaft 32 is thus positioned the control member 31 will be in "on" or active position to start the pump motor. These two projections are integrally connected with each other and also with a cam 47, the purpose of which will be later described.

The control member 31 is held in "off" or inactive position by means of the nozzle 8, when in place on its support 33 as above described. It is also held in "off" or inactive position by a latch lever 48 (Figs. 2 and 5). This lever is pivotally supported intermediate its ends from a stud 49. This stud is fixed to cross plate 34, as shown in Fig. 7. One end of latch lever 48 is adapted to abut a shoulder 50 formed on the hub of lever 37. The latch lever 48 is moved from one of its extreme positions to another with a snap action by means of a toggle mechanism. A toggle link 51 is pivoted at its upper end on the stud 49 in back of the latch lever 48 as viewed in Fig. 5. Actually, this link has a hub on which the latch lever 48 is pivotally mounted as shown in Fig. 7. The lower end of link 51 is pivotally connected to the upper end of a second toggle link 52, the lower end of which is slideable in a lug 53 struck up from the cross plate 34. A spring 54 coiled around link 52 acts between the lug 53 and a shoulder on link 52 to hold the toggle links in one or the other of their extreme positions. The upper toggle link 51 has two cylindrical studs 55 and 56 which extend both forwardly and rearwardly from the link as best shown in Fig. 7. The forwardly projecting parts of these studs lie in the path of the latch lever 48 and the latter is moved by the toggle mechanism through one or the other of these projections. As shown in Fig. 5, the projection 55 abuts the latch lever and holds it in the illustrated position in which it latches shaft 32 against clockwise movement. The rearwardly projecting part of stud 55 (Figs. 3 and 7) lies in the path of the outer end of a lever 57. The latter (Fig. 3) has fixed thereto at a point intermediate its ends a stud 58, which is pivotally mounted in a bearing 59 fixed to cross plate 34. When this lever 57 is turned clockwise as viewed in Fig. 2 or counterclockwise as viewed in Fig. 5 by means to be described, it will engage the rear part of stud 55 and swing the toggle link 51, compressing spring 54 until the pivotal connection between the two toggle links crosses the line that interconnects the centers of stud 49 and the hole in lug 53. Then, spring 54 will suddenly expand and rapidly move the toggle link 51 to carry the projection 56 against the latch lever 48 and move the latter with a snap action in a direction to release the latch from shoulder 50, as shown in Fig. 4. The movement of the latch lever in this direction is limited by the abutment of its upper and right hand end with the hub 60 of lever 57. The rearwardly projecting portion of stud 56, when positioned as shown in Fig. 4, lies in the path of the above described cam 47 (see also Fig. 7) and, when control member 31 is moved counterclockwise into active position to start the pump motor, the cam 47 will engage stud 56 and swing the toggle link 51 in a clockwise direction, compressing spring 54 until the pivotal connection between the two toggle links crosses the aforesaid line of centers, whereupon the spring 54 will suddenly expand and move the toggle links into the positions shown in Fig. 6. In the course of this movement the stud 55 will move lever 48 back against the hub of lever 37 so that when the control member 31 is turned into inactive position to stop the pump motor, the latch 48 will drop behind the shoulder 50 to prevent subsequent movement of the member until the register 24 has been reset.

The release of latch 48, as above described, is effected by movement of the lever 57. Movement of this lever is effected from the register 24 by turning movement of the reset shaft 26 near the end of the register-re-

setting operation. As shown in Fig. 3, a circular disk 61 is slidably keyed to the reset shaft 26 and is held against axial displacement between the end frame 62 of the register and one of the counter wheels 25. Fixed on disk 61 is a pin 63, which at the start and end of a resetting operation occupies the angular position shown in Fig. 2. In the resetting operation, shaft 26 and disk 61 will turn counterclockwise one complete revolution bringing pin 63 back into the Fig. 2 position. Mounted in the path of movement of the pin 63 is one end of a lever 64, which is pivotally mounted intermediate its ends on a shaft 65 that forms part of the register and has a bearing in the end frame 62. The other end of lever 64 is connected by a link 66 (preferably adjustable as to length as indicated) to the outer end of an arm 67 which is fixed at its inner end to a countershaft 68, supported at its ends in bearings in plates 69 and 70, suitably fixed to a pair of corner posts 18. Also fixed at one end to countershaft 68 is an arm 71, the other end of which is connected by a link 72 (preferably also adjustable as to length as indicated), to the described lever 57. The pin 63 on the disk 61 will, as it nears the end of its revolution engage the outer end of lever 64, as indicated in Fig. 4, and depress such end, raising the other end and through link 66, the arm 67 which turns countershaft 68, raising arm 71 and lifting link 72 to swing lever 57 clockwise and cause it to move pin 55 and the toggle links as above described. As soon as the toggle links have been moved across the described line of centers, their movement will be completed by the toggle spring 54 and the lever 57 can then move back to its former position which occurs gradually as pin 63 rides along the lever 64 and finally off the outer end thereof.

Actually, the disk 61 is part of the commercial register and is used to control the operation of a shutter that covers the windows 27 and conceals the numbers on the counter wheels 25 during the resetting operation, all in a manner fully disclosed in the above-named White patent. Briefly the disk 61 has a segment gear 73, for intermittently meshing with the 8 tooth portion of a triplex pinion 74, loosely mounted on the shaft 75 that carries the transfer pinions for the counter wheels 25. This pinion has in one rear transverse section eight teeth; in a central transverse section six teeth and in an outer transverse section four teeth. The last-named teeth control the operation of the shutter, letting it fall at the start of a resetting operation and raising it at the end of a resetting operation. The disk 61 occupies the central transverse section and cooperates with one of the six teeth and one of the four teeth pinion sections as shown in Fig. 4 to hold the pinion against turning except at the start and end of the resetting cycle. For the purpose of this invention, all that is necessary is to add the pin 63 to the above disk although a separate disk with a pin could be mounted on the reset shaft in the same way for the purpose.

It is necessary to prevent resetting of the register during operation of the pump and this is accomplished by preventing axial movement of the resetting shaft 26, whenever the control member 31 is moved out of its "off" position. For this purpose, the member 31 is made to actuate a lever 76, which is pivoted intermediate its ends on the described shaft 65 of the register. One end of this lever 76 is movable in a plane transverse to the axis of the reset shaft 26 and closely adjacent one end thereof (Fig. 3). When the control member 31 moves to "on" position, the lever 76 will be swung clockwise from the position shown in Fig. 2 to carry its right hand end into the path of axial movement of shaft 26, thereby preventing such movement, which as above set forth is necessary in order to reset the counter wheels to zero. As shown, control member 31 and lever 76 are interconnected as follows. The left hand end of lever 76 is connected by a link 77 to the outer end of an arm 78 which

is fixed at its other end to a sleeve 79 mounted to turn on shaft 68. Also fixed to sleeve 76 is an arm 80 which is connected by a link 81 to arm 82 fixed on the shaft 32 of member 31. Thus, as the latter is moved from "off" to "on" position the lever 76 moves into the path of axial movement of the reset shaft 26 and prevents resetting of the register until the control member 31 is moved back to "off" position.

The invention thus provides improved interlocking mechanism between the pump control member of a liquid dispensing apparatus and the resetting means of a register that indicates the amount of liquid dispensed. The invention is designed for use with register resetting means which includes a reset shaft that is movable axially and rotatable to effect resetting and serves to prevent pumping during resetting, resetting during pumping and to compel resetting after each pumping operation.

What is claimed is:

1. In liquid dispensing apparatus of the type having dispensing means, including a pump motor and a control member movable from an inactive to an active position and vice versa to respectively start and stop said motor, and a register, including indicating means arranged to register the quantity of liquid dispensed and means for resetting the indicating means to zero, said resetting means including a reset shaft which is axially shiftable from an inactive to an active position and in the latter position rotatable through one revolution to effect resetting of the indicating means, a latch for holding the control member in inactive position, a disk slidably keyed to the reset shaft and having a pin projecting from one face thereof, a lever having a part lying in the path of rotary movement of said pin and adapted to be moved thereby near the end of the rotary resetting movement of the reset shaft, and means interconnecting said lever and latch for actuating the latter to release the control member at the end of the resetting movement.

2. In liquid dispensing apparatus of the type having

5
